UNITED STATES PATENT OFFICE.

THOMAS B. TAYLOR, OF BIRMINGHAM, ALABAMA, ASSIGNOR TO THE DECATUR CAR WHEEL AND MANUFACTURING COMPANY, OF SAME PLACE.

JOURNAL-BOX.

SPECIFICATION forming part of Letters Patent No. 629,180, dated July 18, 1899.

Application filed November 21, 1898. Serial No. 697,059. (No model.)

To all whom it may concern:

Be it known that I, THOMAS B. TAYLOR, a citizen of the United States, residing at Birmingham, in the county of Jefferson and State of Alabama, have invented a new and useful Improvement in Journal-Boxes, of which the following is a specification.

My improvement relates to self-lubricating journal-boxes for truck-axles, and it is specially adapted for use with mining-cars for ore, coal, &c.

The object of my invention is to provide a journal-box which may be readily detached and replaced without removing the wheel and which also shall be thoroughly efficient for lubricating purposes when in place.

My invention in all its details will be clearly understood from the following description, reference being had to the accompanying drawings, of which—

Figure 1 is an inner end elevation; Fig. 2, a side elevation; Fig. 3, a bottom plan view, and Fig. 4 a vertical central longitudinal section of the box.

My invention relates to the construction of the journal-box into which the inner end of the hub projects and which surrounds the axle and is secured to the truck-timbers. This journal-box where it receives the hub is provided with an annular chamber *t* to receive packing, the function of which is to absorb the oil which gradually leaks from the oil-reservoir through the hub. The box is divided horizontally into two parts—the upper part *A* and the lower part *B*—which fit together by means of a rabbet-joint, as shown at *s*, toward their inner ends. Immediately adjacent to the annular chamber *t* and at each side of the opening for the axle tubular lugs *r r* are provided upon the upper part *A* and analogous lugs *r' r'* upon the lower part *B*, the upper and lower lugs being separated from each other by an interval sufficient to receive nuts *q*. The separate parts of the journal-box are secured independently to the truck-timber and are firmly held together when in place by means of two bolts *C*, threaded toward their lower ends and passing down through the truck-timber and lugs *r r'*, where they receive the nuts *q* and *q'*.

To assemble the journal-box, the upper part

A is first put into place and secured by the nuts *q*, after which the lower part *B* is put into place and secured by means of the nuts *q'*. To secure the nuts *q'* against displacement, a nut-lock is necessary, and I have accordingly provided the following construction: Upon the under side of the part *B*, between the lugs *r'*, a dovetailed projection *p* is provided, and adjacent to it, in line with its center, is a rib *o*, provided with a transverse notch *n*. *D* is a rectangular metal block having upon its inner side a dovetailed recess *m*, fitting the dovetailed projection *p*, and of such length as to enter snugly between the nuts *q'* when the latter are properly in place. Projecting from the center of this block in line with the rib *o* is a lug *l*, provided on its inner face with a notch *n'* in such position as to coincide with the notch *n* when the block *D* is in place between the nuts. To secure the block *D* in place, a wire *k* of suitable gage is passed through the opening formed by the notches *n* and *n'* and twisted or doubled upon itself on the under side of the lug *l*. When it is desired to remove the journal-box in whole or in part for any purpose, the wire *k* is untwisted and drawn out and the nut-lock *D* removed. This permits the nuts *q'* to be unscrewed and the part *B* of the journal-box to fall. Next, if it is desired to remove the upper part *A* also the truck is raised from the axle by means of a lifting-jack and the nuts *q* removed, whereupon the upper part *A* of the journal-box falls. In this way it will be seen that the journal-box may be repacked or repaired or wholly replaced by another without removing the wheel from the axle.

In addition to the advantages mentioned the journal-box described is simple and cheap in the matter of construction, the upper and lower halves being plain castings requiring no cores and no drilling. In operation the packing is placed dry within the chamber *t*, but soon becomes saturated from the reservoir.

What I claim as new, and desire to secure by Letters Patent, is—

1. A journal-box divided horizontally into two parts, said parts being provided with bolt-holes in line with each other at opposite sides

of the opening for the axle, and separated from each other in the region of the bolt-holes for the reception of nuts, in combination with bolts C of such length as to extend through 5 the truck-timber and below the lugs of the lower section of the journal-box when the parts are assembled, and having their lower portions screw-threaded, nuts q fitting the screw-threaded portions of the bolts for securing the upper section of the journal-box 10 in place, and corresponding nuts q' for securing the lower section of the journal-box in place, substantially as described.

2. A journal-box divided horizontally into 15 two parts provided at opposite sides of the opening for the axle with vertical bolt-holes, said parts in the region of the bolt-holes being separated from each other for the reception of screw-nuts, whereby the parts may be 20 secured together and independently to the truck by means of bolts C and nuts q and q',

in combination with a nut-lock attachment for preventing the displacement of the nuts q', substantially as described.

3. In a journal-box having an annular 25 packing-chamber t and divided horizontally into two parts, A and B, the tubular lugs r upon the upper part A on opposite sides of the opening for the axle, and correspondingly-placed tubular lugs r' upon the lower 30 part B separated from the lugs r when the parts are in place for the reception of nuts, whereby the parts may be secured together and to the truck by screw-bolts C and nuts q q', in combination with a nut-lock attachment 35 for preventing displacement of the lower nuts q', substantially as described.

THOMAS B. TAYLOR.

In presence of—

H. G. ROBINSON,

WALTER E. HENLEY.
